PHONOGRAPH STYLUS UNIT OR SIMILAR ARTICLE

Peter E. Pritchard, Skaneateles, N.Y., assignor to General Electric Company, a corporation of New York

Filed May 2, 1960, Ser. No. 60,390

Term of patent 14 years

(Cl. D26—14)

Fig. 1 is a bottom plan view of a phonograph stylus unit or similar article, showing my new design;

Fig. 2 is a front elevational view;

Fig. 3 is a top plan view;

Fig. 4 is a rear elevational view;

Fig. 5 is a side elevational view, the opposite side being substantially a mirror image thereof;

Fig. 6 is a top perspective view; and

Fig. 7 is a bottom perspective view thereof.

I claim:

The ornamental design for a phonograph stylus unit or similar article, substantially as shown and described.
